UNITED STATES PATENT OFFICE.

MORRIS BERNSTEIN, OF PHILADELPHIA, PENNSYLVANIA.

FLYING MACHINE.

Application filed December 29, 1927. Serial No. 243,299.

My invention relates to a new and useful improvement in flying machines, and has for its object to so construct such a machine as to give great stability in flying and to so locate the propellers and apply the power thereto that great speed may be obtained with the least expenditure of energy.

A further object of my invention is to provide against the tendency for such a machine to side slip or turn over and to increase its buoyancy.

A still further object of my invention is to lessen the tendency to fall should the motor become disabled.

With these ends in view, this invention consists in the details of construction and combination of elements set forth and then specifically designated by the claims.

In order that those skilled in the art to which this invention appertains may understand how to make and use the same, I will describe its construction in detail, referring by numerals to the accompanying drawings forming a part of this application, in

25 which:

Fig. 1, is a perspective of a flying machine made in accordance with my invention.

Fig. 2, is a plan view of the machine.

Fig. 3, is a side elevation of Fig. 2.

30 Fig. 4, is a diagrammatical view illustrating the driving mechanism for the auxiliary propellers.

Fig. 5, is a side view of Fig. 4.

Fig. 6, is an end view of Fig. 4.

35 Fig. 7, is an edge view of the transmission housing on an enlarged scale.

Fig. 8, is a plan view of Fig. 7, the upper half of the transmission housing being removed.

40 Fig. 9, is a rear view of Fig. 8 showing the fuselage in section to illustrate the manner of positioning and securing the transmission housing thereto.

Fig. 10, is an enlarged side elevation 45 partly in section of one of the upper hollow wings and one of the air pontoons.

Fig. 11, is a detail view of the shutter actuating mechanism looking from beneath the machine upward.

50 In carrying out my invention as herein embodied, 1 represents the fuselage of my improved aeroplane having the usual side-wise steering vane 2 and the vertical steer-

ing vanes 3 and likewise the usual running gear consisting of the wheels 4 and the skid 5 carried by said fuselage.

6 represents the transmission casing which is preferably made in halves to enclose the transmission shaft 7, the counter shaft 8 and the gears carried by the shafts, and this casing is braced by the strut wires 9 and 10. This casing is secured to the fuselage by brackets 11 in any suitable manner while the cross-wise sections of the casing extend through the side walls thereof in order that 65 the auxiliary propeller hubs 12 may be positioned at a sufficient distance from the sides of the fuselage to allow due clearance for the auxiliary propellers, 12^a.

The forward end of the casing is provided with the flange 13 for securement to either the engine casing 14 or the forward end of the fuselage, while the forward end of the shaft 7 is provided with a suitable member 15 for coupling to the engine shaft 75 carrying the main propeller 16.

The rear end of the shaft 7 has secured thereon a beveled gear 17 which meshes with the beveled gear 18 secured upon the counter shaft 8, while a beveled gear 19 is mounted 80 upon each end of the counter shaft, these last mentioned gears meshing with the beveled gears 20 secured upon the auxiliary propeller shafts 21.

By this arrangement the main propeller 85 and auxiliary propellers are caused to revolve in unison at the desired speeds.

22, 23, 24 and 25 represent the wings of the machine, the former being positioned beneath the fuselage while the wing 23 is 90 positioned just above the fuselage and has a cut-away portion 26 to give clearance to the operator entering, leaving or occupying the cockpit, the opening of which latter is indicated at 27. The wing 25 has its top 95 and bottom walls bowed outward as clearly shown in Fig. 10 to form a chamber 28 while presenting a relatively sharp front edge to the wind and a corresponding rear edge for facilitating the off-flow of the air 100 currents. This wing 25 has mounted thereon the air pontoons 29, here shown as three in number, and so positioned as to stabilize the machine against side swaying; the front and rear ends of these pontoons coming to 105 points to more readily permit their passage

through the air at high speed, and openings 30 provide communication between the interior of the wing 25 and these pontoons.

Each of the pontoons has a multiple valve seat 31 in the top thereof through which air may flow from the interior to the atmosphere, and 32 represents one of the valves for closing upon its seat; it being understood that there is a valve seat and a valve 10 for each of the pontoons, and each of these valves is hinged at 33 and is adapted to be closed by the spring 34 and the opening of each of the valves is under the control of the operator of the machine through the 15 flexible wire or cord 34 attached to the valve and passed downward in any suitable manner into close proximity to the operator's seat.

Leading downward from the wing 25 are 20 three spouts 35 so located that the upper end of each spout will lie beneath the opening 30 of one of the pontoons, while the lower end of each of these spouts is open to the air in the direction of the forward movement of the machine, and within each of these lower ends, is pivoted the double valve or shutter 36, one leaf of the shutter having the lever 37 secured thereto, while the other leaf of the shutter has the lever 38 attached 25 thereto. These levers 37 are connected by the rod 39 while the levers 38 are connected by the rod 40 so that the spring 41 will normally keep all of the shutters closed, the central lever 38 being connected to the rod 35 40 to accomplish this purpose.

42 represents a flexible wire or cord which leads from within easy reach of the operator over the pulley 43 carried by the central lever 37 and is attached at 44 to the central lever 38 so that by drawing upon this wire, 40 all of the shutters will be open simultaneously, thus opening the lower ends of the spouts 35 to the inflow of air.

By the use and arrangement of the multiple wings 22, 23, 24 and 25 and the proper bracing of the same by the stay wires 45 and 46, an exceedingly rigid structure is produced presenting large aeroplane surfaces without undue length of wings and by mounting the pontoons upon the upper wing the machine is more readily held in its course, said pontoons acting after the manner of the keel of a boat, and by arranging the auxiliary propellers as shown relative to the main propeller a further tendency to the maintenance of a steady course is provided and the power of the engine more sufficiently exerted for the driving forward of the machine; consequently effecting greater speed with a given engine capacity.

The particular construction and arrangement of the transmission casing, not only sustains the stress incident to the action of the propellers, but also strengthens the

fuselage, and this is of considerable importance in high speed flying machines.

When the machine is flying and the shutter 36 and valve 32 closed, atmospheric pressure will be maintained within the wing 25, 70 but when it is desired to change this pressure within these members, the opening of the shutters 36 will permit the inflow of air thereby increasing the pressure within the spouts, wing and pontoons provided the 75 valves 32 are closed. When it is desired to release this pressure, the closing of the shutters and the opening of the valves 32 will accomplish this result; on the other hand, when the shutters and valves are closed and 80 air drawn from the wing, spouts and pontoons by any suitable means, a pressure vacuum will be created within these members, thus tending to give the machine buoyancy and prevent the sudden or rapid 85 falling of the same, thereby preventing serious accidents and loss of life.

Of course I do not wish to be limited to the exact details of construction as herein shown, as these may be varied within the 90 limits of the appended claims without departing from the spirit of my invention.

Having thus fully described my invention, what I claim as new and useful is:—

1. A flying machine comprising a fuse- 95 lage; a transmission casing located within the fuselage and secured thereto in such manner as to strengthen said fuselage, the cross-wise portion of said casing extending through the side of the fuselage; auxiliary 100 propeller shafts mounted in the outer ends of the casing; a power shaft extending from the engine through the length-wise portion of the casing; a counter shaft extending through the side wise portion of the casing, 105 gears adapted to transmit power from the power shaft to the counter shaft; gears carried by the counter shaft for transmitting power to the auxiliary propeller shafts; means for coupling the power shaft to the 110 engine, a main propeller adapted to be revolved by the engine; a wing positioned below the fuselage; a series of wings positioned above the fuselage, the top most of said last-mentioned wings being hollow; a 115 series of pontoons mounted upon the top most wings; and means for varying the pressure of air within said top most wings and pontoons.

2. In combination with a multiple wing 120 flying machine, a hollow wing; a series of pontoons mounted upon said wing; openings establishing communications between said wing and pontoons; a series of spouts leading downward from the hollow wing, 125 their lower ends opening in the direction of flight of the machine; a multiple shutter mounted within the open end of each spout; means for opening and closing said shutters in unison; a valve seat located in 130

the top of each of the pontoons; multiple valves adapted to close upon said seats; and means for opening and closing said valves.

3. In a flying machine, a hollow wing, 5 pontoons mounted on said wing, and means for varying the pressure of air within said wing and pontoons comprising valve con-

trolled chutes leading to said wing and valve controlled openings in one of the walls of each of the pontoons, said pontoons and 10 wing being in communication.

In testimony whereof, I have hereunto affixed my signature.

MORRIS BERNSTEIN.
